UNITED STATES PATENT OFFICE.

WILLIAM WEINER, OF GUYMON, OKLAHOMA.

WINDMILL.

1,140,221.

Specification of Letters Patent. Patented May 18, 1915.

Application filed May 16, 1914. Serial No. 839,023.

To all whom it may concern:

Be it known that I, WILLIAM WEINER, a citizen of the United States, residing at Guymon, in the county of Texas and State 5 of Oklahoma, have invented a new and useful Windmill, of which the following is a specification.

The device forming the subject matter of 10 this application is a windmill, and one object of the present invention is to provide novel means whereby the blades of the windmill may, through the medium of a simple structure, be permitted to feather, and through the instrumentality of the same 15 structure, be swung into inoperative positions.

It is within the scope of the invention to improve generally and to enhance the utility of devices of that type to which the present 20 invention appertains.

With the above and other objects in view which will appear as the description proceeds, the invention resides in the combination and arrangement of parts and in the details 25 of construction hereinafter described and claimed, it being understood that changes in the precise embodiment of the invention herein disclosed can be made within the scope of what is claimed without departing 30 from the spirit of the invention.

In the accompanying drawings: Figure 1 shows the invention in side elevation; Fig. 2 is a top plan; Fig. 3 is a fragmental top plan showing one of the blades swung into an inoperative position; Fig. 4 is a fragmental horizontal section showing in top plan, a 35 mechanical movement which may be employed in connection with the windmill herein disclosed; Fig. 5 is a fragmental horizontal section showing in top plan the 40 lever whereby the blades of the windmill are controlled; Fig. 6 is a fragmental side elevation showing in detail the connection between one blade and its actuating lever; 45 and Fig. 7 is a perspective of the connection.

In the drawings there is shown an upright frame 1 of any desired sort provided at its top with a supporting plate 2 and equipped 50 adjacent its lower end with a thrust bearing 8. Journaled for rotation in the supporting plate 2 and upheld by the thrust bearing 8 is a vertical shaft 3 equipped near its lower end with a wheel 4 provided with upstanding pins 5 carrying rollers 6 mounted to move within an open head 7 formed in a

driven member 9 fulcrumed on a post 10 carried by a bracket 11 on the frame 1. By means of a link 12, one end of the driven member 9 is operatively connected with an 60 upright bell crank 14 fulcrumed on a standard 15 supported by the frame 1. The outer end of the bell crank 14 is connected with the pitman 16 of a pump 17.

Noting Fig. 4 it will be understood that 65 each time that the wheel 4 is rotated through the medium of the shaft 3 two strokes will be imparted to the driven member 9 through the medium of the pins 5, motion being transmitted by means of a link 12 into the 70 bell crank 14 and thence into the pitman 16 of the pump 17. If a single stroke only is desired at each revolution of the wheel 4, then one of the pins 5 is removed. Further, by removing both of the pins 5, the element 75 4 may be used as an ordinary band wheel for driving machinery of any sort.

Passing to the windmill construction which forms the subject matter of this application, it will be observed that a spider 80 18 is attached to the shaft 3 above the supporting plate 2, the spider 18 carrying arms 19. The spider 18 and the shaft 3 may be described as a rotatable frame.

In order to simplify the drawings, four 85 arms 19 only are shown, but it will be understood that any desired number of arms may be employed. Mounted on each arm 19 adjacent its outer end is an upright stud 20 upon which is pivoted for horizontal 90 swinging movement a blade 21. If desired, guys 22 may extend from the upper end of each stud 20 to a cap 23 secured to the upper end of the shaft 3. On the side face of the blade 21 is a bracket 24 receiving pivotally 95 an eye 25 formed at one end of a lost motion connection 26 permitting a feathering of the blade 21 and having a shoulder 27 and provided with a terminal finger 28. That portion of the connection 26 which lies between 100 the shoulder 27 and the finger 28 is mounted to slide in an ear 29 formed on one end of a lever 30 fulcrumed as indicated at 31 for horizontal swinging movement on a support 32 outstanding from the arm 19 and constituting to all intents and purposes a part of the arm. The blade 21 and the lever 30 may be described as coöperating elements, the connection 26 being pivoted at 25 to one of said coöperating elements and being mounted 105 to slide in the other of said coöperating elements. By means of a link 33, the inner 110

end of the lever 30 is connected with a bell crank lever 34 fulcrumed for vertical swinging movement as shown at 35 upon the arm 19.

5 In order to control the several bell crank levers 34 a slide or actuating element is mounted to reciprocate on the shaft 3. This slide is a composite structure and includes a disk 36 located immediately above the inner 10 ends of the bell crank levers 34 and adapted to engage the same. By means of connections 37, the disk 36 is united with a sleeve 38 mounted to slide vertically on the shaft 3 below the supporting plate 2. A compression spring 39 is interposed between the 15 arms 19 at their point of intersection, upon the one hand, and the disk 36. The tendency of the spring 39 is to elevate the disk 36 and the sleeve 38.

20 As will be understood best from Fig. 5 when this figure is compared with sundry other figures of the drawings, a lever 40 is fulcrumed at one end upon the frame 1, as shown at 41, the lever 40 extending around 25 the sleeve 38 and engaging the lower portion of the sleeve to effect a depression of the sleeve and the disk 36. By means of connection 42, the lever 40 is united with a lever 43, fulcrumed as shown at 44 on the 30 frame 1. The free end of the lever 43 may be swung downwardly and be engaged beneath a pin or like projection 45 on the frame 1.

When the windmill is running, the blades 35 stand out from the ends of the arms 19 in alignment with the arms as shown in Fig. 2. Under such circumstances, the shoulder 27 on the connection 26 abuts against the ear 29 on the lever 30. The bell 40 crank lever 34 moves in a plane at right angles to the plane of movement of the lever 30 and consequently the link 33, coöperating with the bell crank lever 34, prevents the 45 blade 21 from swinging, under the pressure of the wind, beyond the outstanding position shown in Fig. 2. When, however, the wheel has rotated sufficiently, so that the wind pressure is brought against the rear face of any blade 21, such blade will be permitted to feather slightly, the connection 26 sliding in the ear 29 of the lever 30 until the finger 28 on the connection engages the ear. Obviously, owing to this feathering operation, the wheel will rotate readily and with 50 a minimum expenditure of wind pressure.

Now when it is desired to dispose the blades 21 in inoperative positions, as shown in Fig. 3, the lever 43 is pressed downwardly and its free end is engaged beneath 60 the pin 45. The connection 42 is drawn downwardly, the lever 40 is tilted, the sleeve 38 is depressed, and by means of the connection 37, the disk 36 is depressed, the spring 39 being put under compression. When the 65 disk 36 moves downwardly, the same will en-

gage the inner ends of the bell crank levers 34, tilting the bell crank levers on their fulcrums 35 and imparting movement to the levers 31 through the medium of the links 33. When the levers 30 are actuated, the 70 ears 29 on the levers engaging the shoulders 27 of the connections 26 will swing the blades 21 inwardly into the inoperative positions shown in Fig. 3 of the drawings. The wheel now will not rotate readily for two 75 reasons. First, because the blades 21 have been swung inwardly to such an extent that their centers of effort have a relatively short power arm; and secondly, because the disk 36, bearing upon the inner ends of the levers 34 will tend to act as a brake. As soon as the pressure of the disk 36 on the inner ends 80 of the bell crank levers 34 is released, the wheel will begin to rotate slowly, and, ultimately, under the wind pressure, the blades 85 will be swung outwardly into the positions shown in Fig. 1, whereupon the wheel will at once begin to rotate rapidly.

Having thus described the invention, what is claimed is:—

1. In a device of the class described, a frame; a shaft journaled therein; an arm projecting from the shaft; coöperating elements comprising a blade pivoted to the arm and a primary lever fulcrumed on the 95 arm; a connection pivoted to one of said coöperating elements and slidable in the other of said coöperating elements to permit a feathering of the blade, the connection having a shoulder adapted to engage said other coöperating element to swing the blade into an inoperative position when the lever is actuated; a secondary lever fulcrumed on the arm; a connection between the levers; a slide mounted to reciprocate on the shaft 100 and adapted to engage the secondary lever; yieldable means for moving the slide away from the secondary lever; and means under the control of the operator for moving the slide into engagement with the secondary 105 lever.

2. In a device of the class described, a frame; a shaft journaled therein; an arm projecting from the shaft; coöperating elements comprising a blade pivoted on the 115 arm and a primary lever fulcrumed on the arm; a connection pivoted to one of said coöperating elements and slidable in the other of said coöperating elements to permit a feathering of the blade, the connection having a shoulder adapted to engage said other coöperating element to swing the blade into an inoperative position when the lever is actuated; a secondary lever fulcrumed on the arm; a connection between the levers; a 120 slide mounted to reciprocate on the shaft and adapted to engage the secondary lever; and means under the control of an operator for actuating the slide with respect to the 125 secondary lever.

3. In a device of the class described, a frame; a shaft journaled therein; an arm projecting from the shaft; coöperating elements comprising a blade pivoted on the 5 arm and a primary lever fulcrumed on the arm; a connection pivoted to one of said coöperating elements and slidable in the other of said coöperating elements to permit a feathering of the blade, the connection having a shoulder adapted to engage said other coöperating element to swing the blade into an inoperative position when the lever is actuated; and means for actuating the lever.
- 10 4. In a device of the class described, a frame; a shaft journaled therein; an arm projecting from the shaft; coöperating elements comprising a blade pivoted on the arm and a lever fulcrumed on the arm; a 15 connection pivoted to one of said coöperating elements and slidable in the other of said coöperating elements to permit a feathering of the blade, the connection having a shoulder adapted to engage said other coöperating element to swing the blade into 20
- 25
- an inoperative position when the lever is actuated; a bell crank fulcrumed on the arm and movable in a plane at an angle to the plane of movement of the lever; a connection between the bell crank and the lever; 30 and movable means mounted on the shaft for engaging the inner end of the bell crank.
5. In a device of the class described, a frame; a shaft journaled therein; an arm projecting from the shaft; a blade pivoted 35 to the arm; a lever fulcrumed on the arm; a connection pivoted to the blade and slidable in the lever, the connection having shoulders adapted to engage opposed portions of the lever to permit a sliding movement of the connection; and means for actuating the lever.

In testimony that I claim the foregoing as my own, I have hereto affixed my signature in the presence of two witnesses.

WILLIAM WEINER.
